UNITED STATES PATENT OFFICE.

L. D. COOK, OF MINNEAPOLIS, MINNESOTA.

AUTOMATIC AUTOMOBILE PARKING DEVICE.

Application filed January 8, 1926. Serial No. 80,114.

My present invention has for its object to provide an automatic device for use in parking automobiles, and to this end it consists of the novel devices and combinations of devices hereinafter described and defined in the claims.

As is well known, it is very difficult to park cars in garages having narrow aisles and posts without repeatedly backing and turning the car, and this is often difficult to do without striking another automobile or post. Furthermore, it is very difficult to park cars close together so that they take up a minimum amount of space, and in certain garages, dollies are required to move cars into their parking spaces.

By the use of my invention, automobiles may be parked and moved into and out of their stalls or parking spaces by a continuous traveling and turning movement, without danger of striking another automobile or post, and may also be parked close to another car.

In the accompanying drawings, which illustrate the invention, like characters indicate like parts throughout the several views.

Referring to the drawings:

Fig. 1 is a fragmentary view of a garage in horizontal section having the invention installed in several of the stalls therein, and further illustrates in plan two automobiles, one of which is parked and the other of which is being parked into its stall by the use of the invention;

Fig. 2 is a plan view, on an enlarged scale, of one of the trucks in normal position with its pocket shown in different positions by means of broken lines;

Fig. 3 is a view partly in side elevation and partly in longitudinal central section taken on the line 3—3 of Fig. 1, on an enlarged scale;

Fig. 4 is a detail view principally in section taken on the irregular line 4—4 of Fig. 3;

Fig. 5 is a transverse vertical section taken on the line 5—5 of Fig. 3;

Fig. 6 is a fragmentary detail view in section taken on the line 6—6 of Fig. 3;

Fig. 7 is a detail view in section taken on the line 7—7 of Fig. 1, on an enlarged scale;

Fig. 8 is a detail view in section taken on the line 8—8 of Fig. 1, on an enlarged scale; and indicating a portion of a tire-equipped wheel by means of broken lines; and

Fig. 9 is a side elevation of one of the wheel guards.

The numeral 10 indicates a garage having a row of laterally spaced posts 11 between which are stalls or parking spaces 12 for automobiles, indicated as an entirety by the numeral 13 with the exception of their rear wheels 14 and 15. Running in front of the stalls 8 is an aisle 16 between two opposite door openings in said garage, not shown. The parts thus far described have been illustrated simply for the purpose of showing the invention installed in a garage.

Referring now in detail to the invention there is secured to the floor of the garage 10 in each stall or parking space 12 a pair of laterally spaced track rails 17 that extend longitudinally thereof and represent the left-hand wheel track of an automobile either going in or out of the respective stall 12. As shown, each track rail 17 is hollow and substantially square in cross section and has outwardly extended side flanges at the top thereof. The bottoms of the track rails 17 are convex in cross section and in the tops of said rails are longitudinal slots 18 that are directly over the crowns of said bottoms. Said track rails 17 are set into the floor of the garage 10 so that their tops are flush therewith. It is important to note that the track rails 17 within each stall 12 are straight and their forward end portions are extended outward of the stalls into the aisle 16 and are curved laterally.

Mounted to travel over each pair of track rails 17 is a low truck 19 having four caster wheels 20 within said rails and arranged to run on the crowned bottoms thereof. These truck wheels 20 are journaled on fork-like brackets 21 having journaled on their prongs vertically disposed anti-friction rollers 22 arranged to engage the sides of the track rails 17. The stems 23 of the brackets 21 extend upward through the longitudinal slots 18 in the track rails 17 and are swivelled to the platform 24 of the truck 19.

On the truck platform 24 is a raised turntable 25 on which is mounted a truck body 26 swivelled thereto for horizontal movement by a king bolt 27 that extends upward through the platform 24 and is secured to said body for turning movement therewith. This truck body 26 is provided with an elongated pocket 28 for the wheel 14, the bottom of which is transversely curved in cross sec-

tion and the sides of which are parallel to receive and closely engage the tread and sides of the tire of said wheel.

On end of the pocket 28 is closed by a pair of horizontal swinging gates 29 and the other end thereof is closed by a vertically swinging gate 30. The gates 29 are secured to the sides of the pocket 28 by spring hinges 31 for inward swinging movement and are yieldingly held closed against a stop rib 32 on the body 26 which prevents outward swinging movement of said gates. Each gate 29 is provided with a stop extension 33 attached thereto for inward swinging movement in a vertical plane by a spring hinge 34. A depending stop flange 35 on the hinged lower edge of each gate extension 33 overlaps the outer face thereof and holds said gate extension in an upright position and against outward swinging movement. The gate 30 has its lower horizontal edge attached to the respective end of the truck body 26 by a hinge pin 36. This hinge pin 36 is loosely mounted on the truck body 26 and rigidly secured to the gate 30 for movement therewith, and has on its left-hand end a crank arm 37 arranged to engage a cam lug 38, on the left-hand track rail 17 near the curved front end thereof, during the travelling movement of the truck 19 into the stall 12 to automatically close the gate 30.

To hold the gate 30 closed there is provided a spring-projected latch 39 mounted in a bushing 40 on the left hand side of the pocket 28 with its inner end projecting in the path of movement of said gate during its movement to a closed position and to be cammed thereby into an inoperative position to allow said gate to pass the latch 39, and when released, to project in front of said gate and hold the same closed. To automatically retract the latch 39 and allow the gate 30 to swing open under the action of gravity when the truck 19 is in its outermost position and during the turning movement of the truck body 26 on said truck, there is inserted between the bushing 40 and a cam surface 41 on the outer end of the latch 39 a cam finger 42 normally held retracted by a coiled spring 43. This cam finger 42 is rigidly secured to the outer end of an arm 44 slidably mounted in a bearing 45 on the left-hand side of the pocket 28. This arm 44 is connected by a bell crank 46 to the upper end of a vertical plunger 47 mounted in a bearing 48 on the left side of the pocket 28, and its lower end rests on the platform 24. Secured to the platform 24 are cams 49 arranged to be engaged by the plunger 47 during the swinging movement of the truck body 26 on the truck 19 to raise said plunger and project the cam finger 42 and release the latch 39.

When the truck 19 is in its outermost position its body 26 is stopped in a predeter-

mined position in which the pocket 28 extends at a right angle to the straight portions of the track rails 17 and parallel to the aisle 16 by a fixed stop 50 secured on the platform 24 and a stop 51 on the truck body 26. A spiral spring 52 is mounted in a recess formed in the opposing faces of the turn table 25 and truck body 26 and has one of its ends anchored to said turn table and its other end anchored to the king bolt 27 and is under strain to swing the truck body 26 to the left until stopped by the engagement of the stop 51 with the stop 50, as shown in Fig. 2.

The end portions of the side walls of the pocket 28 are extended materially outward of the truck body 26 in flaring relation and afford a pair of guide flanges 53 at each end of the pocket 28 for directing the wheel 14 into the pocket 28.

The movement of the automobile 13 into its stall 12 is limited by a stop 54 secured to the floor of the garage 10 and arranged to be engaged by the wheel 15 of said automobile.

To prevent the automobile 13 from being turned too quickly when moving out of its stall 12 there is secured to the floor of the garage 10, at the right-hand side of said stall, a longitudinally extended guard 55 made up of a plurality of axially spaced rollers 56 on a shaft journaled in end and intermediate bearings 57 secured to the floor of the garage 10. It will be noted that the end bearings 57 are rounded so that they do not form a sharp obstruction in case the same should be struck by one of the tires of the automobile. The purpose of providing the guard 55 with rollers is to form an abutment that will not scrape or otherwise damage the sides of a tire. Secured to the end bearings 57 and extending longitudinally over the rollers 56 is a rod 58 that serves as a guard to prevent anyone from stepping on said rollers which might cause a person to stumble or fall.

To assist the truck 19 in swinging the rear end of one of the automobiles 13 into its stall 12 as the same is being parked there is provided a short curved track section 59 for the right-hand rear wheel 15 of said automobile. This track section 59 extends into the aisle 16 and is concentric with the curved front end portions of the track rails 17. As shown, the track section 59 is in the form of a plate, the longitudinal edge portions of which are rigidly secured to the floor of the garage 10, and the intermediate portion of said track section is convex in cross section. Formed in the crowned portion of the track section 59 are a multiplicity of transversely extended ribs 60 that are oblique to the radial lines of said track section. The purpose of thus shaping the track section 59 and providing the same with the ribs 60 is to cause the wheel 15 to be

crowded or moved toward the left or in other words, toward the truck 19 when the automobile 13 is being parked into its stall 12.

Just rearward of the track section 59 and forming an extension thereof is a four wheel truck 61 arranged to run in track rails 62 that extend transversely of the track rails 17. Said track rails 62 are like the track rails 17 and are set into the floor of the garage 19. A coiled spring 63 holds the truck 61 centered. It will be noted that the guard 55 is just to the right of the truck 61.

When the stalls 12 are empty the trucks 19 are positioned on the curved end portions 15 of the track rails 17 and the bodies of said trucks are yieldingly held by the springs 52 so that their wheel pockets 28 extend into the aisle 16 and parallel thereto. At this same time, the gates 29 are open.

To park one of the automobiles 13 in one of the parking spaces 12, which is being driven along the aisle 16 from the right, the front left-hand wheel of said automobile will be steered so as to pass on either side of the respective pocket 28 or through said pocket. In case said wheel is driven through the pocket 28 the gate 29 will be automatically opened thereby and the open gate 30, the free end of which rests on the floor of the garage 25 10, will act as a runway for said wheel. The forward movement of the automobile is continued until the rear wheel is run into the pocket 28 and said wheel supported on the truck 19. During the movement of the wheel 30 14 into the pocket 28 the gates 29 having been automatically opened by said wheel and then closed by the spring hinges 31. With the rear wheel 14 supported on the truck 19 the front wheels of the automobile are turned 40 sharply so as to move the front end of the automobile to the right and then the automobile is backed into its stall 12. The initial backing movement of the automobile will cause its wheel 14 to engage the extensions 45 33 as an abutment and thereby cause the truck 19 to travel with said wheel. During the turning of the automobile the pocket 50 freely swings with the wheel 14 on the truck 19 and the wheel 15 will travel on the track section 59 and be crowded toward said truck, as previously described. As the truck 19 moves from the curved sections of the track rails 17 onto the straight portions thereof the crank 37 will engage the cam 38 and close 55 the gate 30 so that in case it is necessary to move the car forward during the parking thereof the truck 19 will move with the wheel 14.

During the backing movement of the automobile into its stall 12 the truck 19 moves on the track rails 17 and automatically guides the car into its stall without danger of striking an adjacent automobile or one of the posts 11.

During the movement of the automobile

13 out of its stall 12 the wheel 14 engages the closed gate 30 and causes the truck 19 to travel therewith. Just before the truck 19 is stopped by the outer ends of the track rails 17 and while the pocket 28 is being turned on the truck 19 during the turning of the automobile either to the left or the right the plunger 47 engages one of the cams 49 and thereby releases the latch 39 and allows the gate 30 to open. As soon as the wheel 14 is passed out of the pocket 28 and over the open gate 30 the spring 52 automatically resets the pocket 28.

In turning the automobile to the right when moving out of its stall 12 the truck 19 will of course swing to the left on the curved portion of the track rails 17, and during this movement the wheel 15 will be on the transversely movable truck 61 which will be carried by said wheel toward the tracks 17 as the truck 19 swings to the left and permit the rear end of the automobile to swing to the left until the wheel 14 passes from the pocket 28. As soon as the wheel 15 is moved from the truck 61 the spring 63 will return the same to normal position.

In case an automobile enters the garage from the left the same will be backed so as to cause its rear wheel to enter the respective pocket 28. The remainder of the parking of the automobile when thus entering the garage will be the same as that previously described.

From the above description it is evident that an automobile may very quickly and easily be parked into a relatively narrow stall from a narrow aisle without danger of damaging an automobile by striking a post or another automobile, and at the same time position the automobile close to another automobile.

The purpose of providing the gates 29 with the gate extensions 33 is to permit said extensions to yield if struck by a bumper or other part on a vehicle when moving over the truck 19.

What I claim is:

1. In a device of the kind described, the combination with a track, of a truck arranged to run on the track and adapted to support one of the wheels of a vehicle and be moved thereby to guide the vehicle during either a forward or backward travelling movement thereof.

2. In a device of the kind described, the combination with a track, of a truck arranged to run on the track, said truck having a body provided with a wheel pocket adapted to receive one of the wheels of a vehicle when run onto said body to secure said body thereto, whereby the truck will be moved by the vehicle to guide the same.

3. The structure defined in claim 2 in which the body is swivelled to the truck for horizontal swinging movement.

4. The structure defined in claim 2 in which the body is swivelled to the truck for horizontal swinging movement, said pocket having an open end.
5. The structure defined in claim 2 in which the body is swivelled to the truck for horizontal swinging movement, said pocket having an open end, the sides of the pocket being extended forward of the open end thereof in flaring relation to afford guide flanges.
6. The structure defined in claim 2 in which the body is swivelled to the truck for horizontal swinging movement, said pocket having an open end, and in further combination with a gate for closing the open end of the pocket to lock said wheel therein.
7. The structure defined in claim 2 in which the body is swivelled to the truck for horizontal swinging movement, said pocket having an open end, and in further combination with a gate hinged to the truck for closing the open end of the pocket and arranged to be turned down in front of the pocket to afford a runway for said wheel, and means for holding the gate closed.
8. The structure defined in claim 2 in which the body is swivelled to the truck for horizontal swinging movement, said pocket having an open end, and in further combination with a gate hinged to the truck and closing the open end of the pocket, automatic means for closing the gate during the backward movement of the truck on the track, and a latch for holding the gate closed.
9. The structure defined in claim 2 in which the body is swivelled to the truck for horizontal swinging movement, said pocket having an open end, and in further combination with a gate hinged to the truck at the open end of the pocket and closing the open end of the pocket, automatic means for closing the gate during the backward movement of the truck on the track, a latch for holding the gate closed, and automatic means for operating the latch to release the gate during the forward movement of the truck on the track.
10. The structure defined in claim 2 in which the body is swivelled to the truck for horizontal swinging movement, said pocket having an open end, in further combination with means for stopping the body in a predetermined position in respect to the truck, and a spring for returning the body to normal position.
11. In a device of the kind described, the combination with a track, of a truck arranged to run on the track and having a swivelled body with a wheel pocket adapted to receive and support one of the wheels of a vehicle, whereby the truck will be moved on the track by the vehicle to guide said vehicle, and means for automatically moving said body to a predetermined position in respect to the truck to set the wheel pocket transversely of the track.
12. The structure defined in claim 11 in which the track is laterally curved at said predetermined position of the truck.
13. The structure defined in claim 11 in which the track is laterally curved at said predetermined position of the truck, and in further combination with a curved track section concentric with the curved portion of said track.
14. The structure defined in claim 11 in which the track is laterally curved at said predetermined position of the truck, and in further combination with a curved track section concentric with the curved portion of said track, said track section being convex in cross section and having transverse ribs that are oblique to the radial lines of said track section.
15. In a device of the kind described, the combination with a track having a laterally curved portion, of a truck arranged to run on the track and having a swivelled body with a wheel pocket adapted to receive and support one of the wheels of a vehicle, whereby the truck will be moved on the track by the vehicle to guide said vehicle, and a secondary truck arranged to support a second wheel of the vehicle and be moved thereby transversely of said track when the first noted truck is travelling on the curved portion of said track.
16. The structure defined in claim 2 in which the body is swivelled to the truck for horizontal swinging movement, said pocket having open ends, and in further combination with a gate for closing the open ends of the wheel pockets for locking a wheel therein.
17. In a device of the kind described, the combination with a plurality of laterally spaced tracks, of a truck arranged to run on each of said tracks, each truck being adapted to support one of the wheels of a vehicle to be moved thereby to guide the vehicle during either a forward or backward travelling movement thereof, the spacing of said tracks being such as to permit the opposite wheel of said vehicle from the truck to run on the floor between adjacent tracks.
18. The structure defined in claim 1 in which said truck has a swivelled body.
- In testimony whereof I affix my signature.

L. D. COOK.
